UNITED STATES PATENT OFFICE.

HARRIE A. BALLARD, OF ASHLAND, MASSACHUSETTS, ASSIGNOR, BY MESNE ASSIGNMENTS, TO THE BOYLSTON MANUFACTURING COMPANY, OF BOSTON, MASSACHUSETTS, A CORPORATION OF NEW JERSEY.

LASTING AND TACKING MACHINE FOR SHOES.

No. 878,854.

Specification of Letters Patent.

Patented Feb. 11, 1908.

Application filed April 13, 1903. Serial No. 152,327.

To all whom it may concern:

Be it known that I, HARRIE A. BALLARD, of Ashland, in the county of Middlesex and State of Massachusetts, have invented certain new and useful Improvements in Lasting and Tacking Machines for Shoes, of which the following is a specification.

This invention has relation to machines for tacking the edge of an upper to an inner sole of a boot or shoe, and it has for its object to provide certain improvements in the mechanism for automatically grasping the upper, so that the operator can draw the upper taut about the last, prior to the actuation of the tack-applying nozzle by the shoe to effect the operation of the machine. Provision is also made for causing the tack to be driven to a greater or lesser depth, as circumstances require. This is accomplished by shifting the range of the driver, and is hereinafter described in detail.

Referring to the drawings, which illustrate one embodiment of the invention, to the details of construction of which, however, the invention is not limited, Figure 1 represents in side elevation a machine embodying my improvements. Fig. 2 represents a portion of the machine, and illustrates the jaws of the pincers in their open position. Fig. 3 represents a similar view and shows the jaws of the pincer closed upon the upper. Fig. 4 represents a section through the upper portion of the pincer. Fig. 5 represents the movable catch on the pincer for engaging the hooked latch. Fig. 6 is a front elevation of the device by which the driver-bar may be shifted longitudinally.

For the details of construction of the tacking mechanism, and the mechanism by means of which the driving mechanism is caused to drive a single tack when the nozzle is raised, as well as the mechanism for feeding the tacks to the driver, reference may be had to the patent to E. Woodward, No. 389,275, dated Sept. 11, 1888; and also to my co-pending application, Serial No. 152,326, filed concurrently herewith.

On the drawings, the tack-delivering member or nozzle is indicated at 10. The driver 100 is actuated by a cam 12 on a shaft 11, the latter being provided with a loose pulley 13 containing a clutch 14. The movement of the clutch is controlled by the lever 140 and trip-mechanism, shown in

Fig. 1, by which when the nozzle 10 is forced upward, the shaft 11 is permitted to rotate once, to effect the driving of a single tack and to stop at the completion of a single rotation. The mechanism for accomplishing this operation is not fully illustrated or described, as it forms no part of the present invention, being illustrated in detail in the Letters Patent of Woodward hereinbefore referred to.

In order that the upper may be properly drawn about the last by the operator, prior to the insertion of a tack through the upper into the inner sole, a pincer is provided and is arranged in close proximity to the nozzle. Preferably one of the pincer members is apertured so that the nozzle may extend therethrough, in order to deliver a tack in proper relation to the stretched portion of the upper that is laid over the edge of the inner sole.

In conjunction with the pincer, mechanism is provided by means of which the advent or presentation of the shoe to the pincer causes the jaws of the pincer to close automatically upon the edge of the upper which is inserted between them by the operator. The operator may then draw the upper taut over the last and wipe the edge thereof down over the edge of the inner sole, and with practically the same motion move the shoe so as to engage the nozzle and lift it sufficiently to trip the mechanism by means of which the driver is caused to drive a single tack or fastener into the shoe.

In my copending application hereinbefore referred to, the pincers are caused to close upon the upper by the engagement of the shoe with a feeler located so as to project below or beyond the jaws of the pincer, but according to the present invention, the simple movement of the pincer itself effects the automatic closing of the jaws upon the work, this movement of the pincer being substantially in the lines of movement of the nozzle.

The pincer consists of two members 17 18, which are pivoted together intermediate of their ends by a stud 19. Said members are provided with the jaws *a* and *b*, which are serrated as shown to engage the upper firmly so as to prevent it from slipping between them. The member 18 is further provided with a wiping surface *c* by means of which the edge of the stretched upper may be laid

flat over the edge of the inner sole. The member 18 is extended rearwardly as at 20, and is pivoted upon a stud 21, projecting from the head of the machine. A spring 22, 5 connected to the extension 20 of the member 18 rocks said member and said member 17 normally downward to the position shown in Fig. 2. The two members 17 18 are socketed to receive a compression-spring 24 between 10 them, as shown in Fig. 4, this spring serving to automatically close the jaws upon the work when permitted. The tension of the spring may be varied by an adjusting screw 25. The nozzle 10 extends into a slot 26 15 formed in the member 18 and in the wiping surface c.

31 indicates a hooked latch which extends through an aperture 29 in the top of the member 17, and the hook of which is adapted 20 to engage a movable catch 30, mounted to slide in the guideway formed in the said member 17. The hooked latch 31 is bent around the driver bar 100 and is connected to an arm 33 on an upright shaft 34, journaled in a bearing 36 formed on the head of the machine. To the upper end of the rock-shaft 34 is connected another arm 35, held against the rear face of the cam 12 by a spring 37. The said rear face of the cam 12 is formed 30 with a bunch or projection for rocking the arm 35 and thereby rocking the shaft 34 to move the hooked latch 31. The catch 30 is provided with a member 28, pivoted thereto and held in alinement therewith, by a spring 35 27. When the jaws of the pincer are open, this member 28 lies above the feeler 26, which is fulcrumed upon a stud 40 and which is connected to the member 18 of the pincer by a screw 41. The stud 40 is secured in any 40 immovable portion of the head, so that when the pincer is moved upward bodily, the feeler 26 is caused to swing upward about said stud 40, so as to engage the member 28 and lift the catch 30 against the tension of a spring 43 so 45 as to disconnect the catch from the latch 31. This allows the spring 24 to force the upper end of the pincer 17 away from the latch 31 but as the movement is not sufficient to entirely disengage the pincer and the latch, the 50 latch may, upon subsequent movement, advance under the catch 30.

In practice, the operator presents a shoe to the machine when the parts are in the position shown in Fig. 2. The edge of the upper 55 is inserted between the serrated jaws of the pincer, and the shoe is moved upward so as to raise the pincer and cause the tripping of the latch from the catch, and allow the spring 24 to close the jaws of the pincer upon 60 the upper. The operator is then able to draw the upper around the last and lay it upon the inner sole. When this is being accomplished, the operator is moving the shoe upward until it comes in contact with the nozzle and lifts it to set in motion the tacking

mechanism. After one tack is driven, the machine stops automatically.

The closing of the jaws causes the member 28 to swing away from the member 26, thus permitting the catch 30 to be drawn downwardly upon the end of the latch 31 by the spring 43.

During the rotation of the shaft 11, the arm 35 rides off from the bunch or projection on the cam 12, and the latch 31 moves forward so that its hook slips under the catch 30; and as the shaft completes its revolution, the projection or rise forces back the arm 35 so as to rock the shaft 34 and draw the hooked latch and the catch to the right so as 80 to open the pincer and hold it in open position; and as the shoe is moved downward by the operator, the feeler 26 drops and the member 28 slips into position above it. From this description, it is apparent that the operator may manipulate the upper as much as he desires by the aid of the pincer to draw said upper taut about the last and lay it properly over the edge of the inner sole, before he sets the machine in motion to effect the driving 90 of the tack.

It will be understood that the shoe is supported upon a jack 50, and that mechanism which is not shown is employed, by means of which the operator may raise and lower the 95 jack to just its proper position, and is swung by foot power toward and from the standard of the machine, so as to move the work longitudinally of the horizontal portion 20 of the gripper member, as well as vertically 100 to actuate the nozzle 10 and effect the driving of the tack.

In addition to the described movement of the pincer as a whole, it has a movement transverse to the sole of the shoe, and substantially in parallelism with the plane of the sole. To accomplish this, the portion 20 is provided with a slot 201, through which the stud 21 extends. The pincer member 18 is provided with a bunch or cam portion 23, which is adapted to engage the stationary portion 32 of the machine or tack-guide, as the said member swings upward. The effect of this is to draw the pincer as a whole longitudinally of the portion 20 against the tension of the spring 22, so that the wiping surface c on the pincer wipes the upper over the edge of the inner sole with a drawing stroke. The spring 22 operates not only to swing the pincer bodily downward but also 120 to move it to the right in Fig. 2, as it moves downward.

In Figs. 1 and 6, an arrangement is shown by means of which the operator can adjust the driving mechanism so as to fully embed the tacks in the work or drive them partially therewith. It will be seen that the path-cam 60 which is actuated by the cam 12 is provided with guides 61 62, in which is mounted a slide 63. Said slide is provided

70

with an angular slot 64, adapted to receive a pin 65 which extends into the driving-bar 100. The slot 64 has one end higher than the other so that by moving the slide 63 to 5 one side or the other, the driver bar 100 may be raised or lowered relatively to the cam 60. By this means, the bar may be adjusted so that it will fully embed the tacks in driving them in the shank and forepart of the sole, 10 or drive them but partway, as in the case of the heel.

The tack-feeding mechanism is not described in detail as it is set forth in my pending application, Serial No. 152,326 filed 15 concurrently herewith.

Having thus explained the nature of the invention; and described a way of constructing and using the same, without attempting to set forth all of the forms in which it may 20 be made, or all of the modes of its use, I declare that what I claim is:—

1. A machine for lasting boots and shoes comprising a movable pincer, and means for causing said pincer to automatically grip the 25 upper on the movement of said pincer by a shoe.

2. A machine for lasting boots and shoes comprising a movable pincer, and means rendered active by the moving of the pincer 30 due to the engagement of a shoe therewith for automatically causing the pincer to grip the upper of a shoe presented thereto.

3. In a shoe-tacking machine, automatic tack-driving mechanism, and a pincer movable toward and away from said driving mechanism and having means rendered active by the movement of said pincer toward said tack-driving mechanism whereby it automatically grips the upper of a shoe presented thereto.

4. In a shoe-tacking machine, a movable, normally open pincer adapted to be moved by a shoe having means rendered active by the movement of said pincer to close the

jaws of the pincer upon the upper of a shoe 45 presented thereto and by which shoe the pincer is moved, and means for automatically opening the jaws of the pincer.

5. In a shoe-tacking machine, a movable pincer, a latch and catch for holding the jaws 50 of the pincer open, and means rendered active by the movement of the pincer for tripping said latch and catch.

6. In a shoe-tacking machine, a movable pincer, a latch and catch for holding the jaws 55 of the pincer open, means rendered active by the movement of the pincer for tripping said latch and catch, and automatic mechanism for causing said latch and catch to open the jaws of said pincer.

7. In a machine of the character described, automatic driving mechanism comprising a movable tack-delivering nozzle, and means rendered active by the movement of said nozzle for effecting the driving of a tack, in 65 combination with a movable member arranged in proximity to the said nozzle in such position that it is engaged by the shoe before the shoe can engage the said nozzle, means on the said member for gripping the 70 upper thereagainst, and mechanism rendered active by the movement of said member for causing the actuation of said gripping means.

8. In a machine of the character described, bodily movable pincers comprising two 75 members, of which one is supported by the other, the said other member being movably attached to the machine, and means rendered active by the movement of the movably attached member by a shoe for causing said 80 members to grip the upper of said shoe.

In testimony whereof I have affixed my signature, in presence of two witnesses.

HARRIE A. BALLARD.
